UNITED STATES PATENT OFFICE.

GEORG ROTH AND KARL KRANKA, OF VIENNA, AUSTRIA-HUNGARY.

RECOIL-OPERATED FIREARM.

SPECIFICATION forming part of Letters Patent No. 634,913, dated October 17, 1899.

Application filed May 12, 1899. Serial No. 716,578. (No model.)

To all whom it may concern:

Be it known that we, GEORG ROTH and KARL KRANKA, subjects of the Emperor of Austria-Hungary, residing at Vienna, Empire of Austria-Hungary, have invented new and useful Improvements in Automatic Firearms, of which the following is a full, clear, and exact description.

The present invention relates to that class of automatic firearms in which a sliding barrel is provided and co-operates to utilize the recoil for ejecting the cartridge-case and reloading the weapon.

The invention may be employed in connection with pistols, rifles, and guns, while the breech-closing device may also be employed in combination with mitrailleuses.

The invention consists of the details of construction hereinafter set forth, and particularly pointed out in the claims.

In order to render the present specification more easily intelligible, reference is had to the accompanying drawings, in which similar numerals of reference denote similar parts throughout the several views.

Figure 1 is a vertical longitudinal section through a pistol, showing the breech closed and the firing-pin in its forward position after the shot has been fired. Figs. 2, 3, and 4 are similar vertical sections through the breech, showing the breech-block in three different positions, as hereinafter particularly described. Fig. 5 is a detail view showing the ejection of the cartridge-case. Fig. 6 is a horizontal longitudinal section on the line xx of Fig. 1, showing means for retaining the breech-block in its rearward position, if necessary. Fig. 7 is a horizontal section on the line yy of Fig. 1, showing means for operating the breech-block by hand. Fig. 8 is a similar section showing a modified form of the device illustrated in Fig. 7. Fig. 9 shows a cross-section through the stock, taken at a point above the magazine-holder and showing a modified form of cartridge-ejector. Fig. 10 is a longitudinal section through a rifle, showing the breech closed and the firing-pin after release; and Fig. 11 is a detail view showing the means for locking the cover of the magazine in position.

The first part of the present invention relates to the peculiar construction of the means

for coupling the breech-block and barrel, which is effected in such manner that the breech-block will not be uncoupled from the barrel until the backward movement of both, due to the recoil, has taken place and while the barrel is performing its forward movement. This arrangement effectually prevents the gases of combustion from firing out at the rear when the breech is opened.

Referring to Figs. 1 to 4 and to Fig. 7, the cover or housing 1, containing and supporting the barrel 11 and the breech-block 13, is attached to the stock or handle 4 of the weapon 65 by means of the hook 2 at the front and fits into a groove 8 at the back or butt end 5, gripping over the said butt by means of a hook 3. The front boring of the said housing is large enough to receive the barrel 11 and the recoil-spring 12, the said barrel being provided with an enlarged rear end 11^a, which fits into and is capable of sliding in the enlarged rear boring of the said housing. The boring of the barrel 11 is enlarged, Fig. 3, at the rear end 75 to receive the front end of the breech-block 13, and it is provided with an annular groove 30, having a cam-like entrance-groove 31, into which lugs 17 at the front end of the breech-block pass and lock when the said breech-block is turned, as hereinafter set forth. The lugs 17, two of which are employed symmetrically arranged, are also provided with cam-surfaces 32, Fig. 4, which engage the cam-grooves 31 of the barrel and effect a partial 85 turn of the breech-block as the end of the same enters or leaves the end of the barrel. The rear barrel end is provided with keys 14, Fig. 7, which slide in grooves 16 of the rear housing-boring, and the firing-pin 9 is also provided with a collar having lugs 15, which also engage the said grooves 16, so that both these parts are not revoluble, but are only free to slide in the housing 1. The internal rear end of the butt is provided with an inwardly-projecting guide-pin 6 to support the breech-block spring 7, said spring being supported at one end against the inside of the butt and at the other end in the hollow firing-pin 9. This spring 7 not only operates the breech-block when it has been uncoupled from the barrel, but also serves to operate the firing-pin when the weapon is discharged.

The breech-block 13 is of cylindrical con-

struction and provided with an internal annular groove 25 and a second internal annular groove 28. Extending backward from the latter and at either side symmetrically arranged are two horizontally-extending grooves 27, the said grooves leading into the annular groove 25 by means of spirally-wound grooves 26, and within these grooves two lugs 10, fast on the firing-pin, lie. It should be mentioned that the annular groove 28 is merely formed for the sake of convenience in cutting the longitudinal grooves 27 and the spiral endings to the same and plays no prominent part in the operation of the breech-block. Short inlet-grooves 29 are provided in the ends of the block 13 to allow of the insertion of the lugs 10 of the firing-pin when the parts are fitted together. From the above description it will be seen that when the block 13 slides on the exterior of the firing-pin the moment the lugs 10 engage the spiral parts of the grooves 26 27 the said block will be turned axially, according to the direction of movement of the same along the firing-pin.

The pivotally-mounted trigger 18 is spring-pressed by means of a spring 33 acting on a pivotally-supported double-arm lever 21, which engages the sear 22 in the following manner: The rear end of the lever 21, which is also acted on by the spring 33, Fig. 1, fits as a sort of ball-and-socket joint into the front end 23 of the pivotally-supported sear 22. The latter is made in two parts, both supported on a common pivot 22^b, the front part 23 having a spring-housing at its rear end, inclosing a spring 34, Figs. 1 and 2, which normally depresses a tail 22^a of the rear part 22. As will be seen from Fig. 1, this arrangement enables a lug 24 on the firing-pin collar to pass over the end of the sear on the rearward recoil of the breech-block; but as the trigger is retained a moment by the finger after the recoil the sear will be kept in such a position that the spring 34, Fig. 2, will force the rear end of the sear up under the lug 24 immediately the same has passed over the said sear end and prevent the pin from again going forward with the barrel under the influence of the recoil-spring 12. Since the recoil takes place instantaneously, immediately the weapon has been discharged, the trigger cannot possibly be released before the lug of the firing-pin has got behind the end of the sear 22, the time being altogether too short.

The operation of the parts described takes place in the following manner: Previous to discharging the weapon the parts are in the position shown at Fig. 4—i. e., the lugs 17 are locked in the annular groove 30 of the barrel end, and the lugs 10 of the firing-pin are at the rear end of the horizontal part 27 of the groove 26 27, the firing-pin being retained by the catch of the lever 21. As soon as the trigger is pulled the lever 21 is tipped on its pivot and the firing-pin released, the movement of the said lever 21 lowering the

front end 23 of the sear 22 and raising the rear end 22 of the same into position to spring back into the path of the firing-pin lug 24 as soon as the latter has passed it at the recoil. On pulling the trigger the firing-pin is free to move forwardly because the lugs of the same were initially in the rear end of the horizontal part 27 of the inner breech-block grooves. As the recoil takes place the sear end 22 yields by means of its spring until the lug 24 has passed it, when it springs back and retains the firing-pin in its extreme rearward position, close to the back end of the butt at 5, as will be clear from Fig. 3. The barrel, however, immediately commences to move forward under the influence of the recoil-spring 12 and pulls the breech-block with it as long as the lugs 10 of the firing-pin move in the horizontal part of the grooves 26 27. As soon as the said grooves have been moved along the lug—i. e., as soon as the breech-block has been slid along the firing-pin far enough to bring the said lugs 10 into the spiral parts 26 of the grooves—the breech-block will be partially turned, which movement brings the lugs 10 into the annular groove 25, but here the rotary movement of the block would cease as the lugs leave the spiral groove were it not for the fact that at this moment the block 95 being detained and the barrel continuing its forward movement causes the cam-surfaces 32 of the forward block-lugs 17 to coöperate with the cam part of the groove 30 at 31, (the block having been turned far enough to bring the parts into coöperation by the action of the lugs 10.) This coöperation gives the block a slight further turn just as it parts from the barrel and locks the lugs 10 in the annular groove 25. The block is now retained by the 105 firing-pin and the barrel completes its forward movement alone, Fig. 3. The cartridge is now forced upwardly into the breech between the breech-block and the rear end of the barrel 11 in the direction of the arrow in 110 Fig. 3. By this time (all the foregoing operations having taken place instantaneously) the trigger will have been released and the sear 22 will by the action of the trigger-spring 33 be lowered out of the path of the detent-lug 24, so that the firing-pin, and with it the breech-block, will move forward under the influence of spring 7 until the front end of the block meets the rear end of the barrel. Immediately this takes place the cam-surfaces 120 32 of the lugs 17 engage the cam or twisted parts 31 of the groove 30 and turn the breech-block on the firing-pin far enough to bring the spiral grooves 26 into position in front of the lugs 10. The forward movement of the block being arrested by the barrel, the firing-pin will now move forward in the said block, turning the same and locking the lugs 17 in the annular groove 30, the firing-pin itself being arrested by the detent of the lever 21 125 just as the lug 10 has gained the rear end of the horizontal groove 27, so that the pin will

be free to move along the said horizontal groove and to discharge the weapon when the trigger is again pulled.

The second part of the invention relates to means for securing the weapon against accidental discharge. In the present case a pistol is illustrated in which the magazine is inserted into the handle from below and detained in position by a detent-pawl 36, which engages a notch in the magazine-wall. The spring 37 of the detent-pawl also fits into a recess in the rear of the trigger below its pivot, and as soon as the trigger has been released—*i. e.*, the finger has been withdrawn from within the trigger-guard—the lower end of the trigger will be forced up toward the guard, so that the finger can only be inserted on pulling the trigger back against the action of the spring 37. At the same time the ends 19 20 of the said trigger are lowered, and in order to prevent the lever 21 from being jerked, which might accidentally cause the weapon to go off, a hook 40 on the trigger engages over the end of the same, as shown at Fig. 1, and effectually prevents its upward movement. Simultaneously a projection 38 at the front upper end of the trigger is raised by the action of the spring 37 and enters a notch 39 of the barrel, thus preventing the inward movement of the same even if the muzzle of the barrel were accidentally struck against any object. This mechanism is described for the purposes of the present application in connection with a weapon having a removable magazine, and consequently a magazine detent-pawl; but in the case of a weapon having a permanent magazine which is filled from the top and provided with a cartridge-lifting device the detent-pawl would 40 of course be dispensed with and the spring 37 would simply rest against a suitable part of the handle or butt, as will be readily understood.

The orifices 43 and 42 of the handle and butt are simply for the sake of lightness and would be covered by the wood casing of the butt.

The third part of the present invention relates to the ejector mechanism, which consists of the following parts: The ejector spring-arm 44, having hook 45, is let into one of the lateral guide-ribs 14 at one end, its free end extending into a groove 47 of the breech-block. To the opposite side of the breech-block is attached the extractor-hook 46. The parts operate in the following manner: When the barrel and breech-block recoil, they are locked together, as described, and on their forward stroke the barrel is unlocked and leaves the block, taking the ejector 44 along with it. As soon as the hook of the ejector has advanced far enough it catches the rim of the cartridge-case and, coöperating with the extractor-hook 46, tips the cartridge-case 65 out of the breech through the lateral opening 48, Fig. 3. The ejector also serves to guide the breech-block in a straight line be-

tween its rotary movements—*i. e.*, when it is in the position shown at Fig. 3. This is effected in that the groove 47 is so formed that at this moment the hook is in a straight part 70 of the groove, and thus prevents the lugs 10, as aforescribed, from entering the spiral grooves 26 before the lugs 17 have engaged and entered the annular groove 30. At this moment the shape of the groove 47 is inclined, Figs. 1 and 5, and thus the hook allows the block to rotate as far as necessary.

When the magazine has been exhausted, the lifter or feed plate for the cartridges may enter the breech between the block and barrel to enable the refilling of the magazine in the well-known manner. This part of the mechanism forming no part of the present invention requires no further description. If, however, an interchangeable magazine is employed, the feed-plate will be taken out with the magazine, and it would be necessary when the magazine is replaced to provide means for drawing back the breech-block, in order to allow the cartridge to enter the barrel. In order to effect this result, a pivoted double-arm lever 49 is provided at the side of the housing 1, said lever having two arms 50 and 51 extending through the wall of the housing into the interior of the magazine-chamber 41 and the breech, respectively. A spring 52 is provided at the opposite end of the lever 49, said spring serving to normally keep the two arms 50 and 51 90 extending into their respective chambers. While there are any cartridges in the magazine the arms will be held back out of the chambers by means of the said cartridges or magazine pressing against the arm 50. As soon, however, as the last cartridge has been fired spring 52 forces the arms 50 and 51 into their chambers and arm 51 will spring forward and prevent the breech-block from coming forward, as shown at Fig. 6. If the magazine is taken out and it is desired to close the breech-block nevertheless, this may be done by simply pressing the short arm of the lever 49 toward the housing, and thereby withdrawing the arms 50 and 51 from the interior of the housing.

If it is desired to open the breech to take out a cartridge or remove a cartridge which has hung fire, a slide 53, as shown in Fig. 7, having the button 54, is employed. This slide is guided in the side of the housing and capable of movement toward the rear of the same when the button 54 is pressed in that direction. The end of the slide, as will be seen from the figure, extends into the housing and engages a lug 15 of the firing-pin. When the slide is pushed back, its end 55 engages the firing-pin, forcing the same into its rearward position, and as the spring of the barrel acts to force the same forward again the breech-block will be unlocked and separate from the barrel, so that the cartridge may be removed. In Fig. 8 a modified form of the slide is shown, in this case a bow 56 being provided, which

is let into the guideways 16 and provided with hooks 57 at its forward ends engaging the lugs 15, the bow extending at the rear of the housing, so that it may be gripped and pulled out, and thus be caused to open the breech. Both these arrangements have the advantage that they remain motionless when the weapon is being fired under ordinary circumstances.

10 In case the spring 7 should get broken or damaged or if the breech-block for any other reason should fail to come forward properly a second slide may be arranged at the opposite side of the housing having the button 15 arranged in proximity to the lug 15 and extending with a hook into the housing, so as to lie at the extreme rear end of the same. This slide may be adapted to be moved in the opposite direction to the slide 53, and thus if 20 the breech-block sticks at the rear end of the housing it may be drawn forward by means of this second slide. The arrangement of the same will be self-evident and needs no illustration, or the slide 53 may be formed round 25 and have an axial movement which may be caused to engage a lateral lug in a notch of the lug 15 and so, if desired, couple the said slide to the firing-pin lug, as will be evident, in which case the slide may also be employed to return the firing-pin and breech-block to the forward position. It is not absolutely necessary that the hooks of the bow 30 56 engage the lugs 15 of the firing-pin, since they could also be made to engage the guide- 35 ribs 14 or any other suitable part.

If the weapon is provided with a fixed magazine, a cartridge-retaining lever will have to be employed, which allows the cartridges to be inserted from above, but prevents their 40 springing out at the top. A device of this kind is shown at Fig. 9. This lever 58 is pivoted on trunnions 59 and extends into the breech, being normally held with its front end in the breech by means of a spring, (not 45 shown,) which is inserted in the spring-box 60 at the opposite end of the lever. As the barrel returns after the recoil it pushes the lever 58 aside and passes it, and as soon as it has passed the lever returns under the influence of its spring and strikes the empty 50 cartridge-case, throwing it out of the breech-block laterally through the opening 48, so that this lever may also be employed as a substitute for the ejector 44, if desired.

55 When it is desired to remove the cartridges from the magazine from above, it is only necessary to press back the lever 58 by means of its button 60 and the lifting or feed plate of the magazine will raise the cartridges up, 60 forcing them out of the magazine into the hand of the operator.

Fig. 10 shows the adaptation of the improvements previously described to a rifle, the breech-block-locking mechanism being exactly the same, as also that of the trigger movement, and since similar numerals of reference are employed and the parts are merely

modified in shape no further description of the same will be necessary, their operation being self-evident from the foregoing specification. The safety device, in connection with the trigger, is omitted in the case of the rifle. It may be mentioned that if the variable-pressure points 19 and 20 are dispensed with the trigger 18 might be made in one piece with 75 the lever 23, in which case the lower arm of the lever 21 might also be omitted. The rear wall 5 of the housing consists of a separate plate, since the handle of the pistol is replaced by the butt of the gun. The recoil-spring 12 is omitted in Fig. 10, because the same is advantageously arranged at the front or muzzle end of the gun and may either be arranged around the barrel or may be mounted in a special housing underneath the same, 80 according to requirement. The rifle is provided with a fixed magazine and a novel cartridge-feed device, the said magazine being filled from the top with the aid of a cartridge-frame.

Finally, the present invention also embraces the peculiar construction and arrangement of the magazine cover or closure and the feed mechanism for the cartridges. The cover 63 is pivotally supported at the under side of the 95 stock and retained closed by a telescopically-acting pin 64 65, Fig. 11, the two parts of which are spring-pressed apart by means of a spring arranged in the space 69. Each of the parts 64 65 carries a forwardly-extending lug 66, 100 adapted to engage in lateral recesses 67, formed in the rear end of the cover, said engagement taking place when the spring within the telescopic pin is free to press the two parts of the same apart. When the parts are 105 pressed together by the fingers of the person manipulating the rifle, the said lugs are so formed that they pass out of the lateral recesses of the cover and allow the same to fall down around its hinge-pin into the position 110 shown in dotted lines in Fig. 10. The feed mechanism for the cartridges consists of the pressure-arm 70, pivoted to the inner surface of the magazine-cover, near the front end of the same, and a frame 71, also pivoted to the 115 same pivot as the lever 70 and having an orifice through which the free end of the said lever extends. To the free end of the frame-plate 71 is hinged the cartridge-carrier plate 72, on which the cartridges rest. If double rows of 120 cartridges are employed, so as to render the magazine less deep, the carrier-plate is formed with a corresponding depression, as indicated at 73 in Fig. 10. The short end of the lever 70 extending beyond its pivot is acted upon 125 by means of the downwardly-spring-pressed bolt 68, which tends to raise the free end of the same, which acts on the under side of the feed-plate 72, causing it to raise the cartridges. This arrangement of the parts has a double 130 advantage. In the first place it enables the plate 72 to accommodate itself to the position and conicity of the cartridge, which result has hitherto been attained by the aid of

a second spring, and in the second place the whole construction has the advantage that when the cover of the magazine is opened the whole feed mechanism falls down or collapses 5 against the cover, as indicated in dotted lines in Fig. 10, owing to the fact that the short end of the lever 70 is removed from the sphere of influence of the downwardly-spring-pressed bolt 68. The arrangement further enables the 10 magazine to be charged with separate cartridges from beneath, which is a double advantage, because this may be done while one cartridge is already in the firing position within the breech. After the last cartridge has 15 been fired the free end of the frame 71 will be forced up into the path of movement of the breech-block and prevent the same from springing forward, retaining it back, and thus enabling the recharging of the magazine.

20 I claim as my invention—

1. In an automatic firearm having a sliding barrel, the combination of a longitudinally-movable firing-pin not capable of axial rotation and a cylindrical axially-revolvable 25 breech-block capable of a telescopic movement on said firing-pin, means for coupling said breech-block and barrel so as to effect a partial turn of the block on the pin to uncouple the barrel and lock the block in its extended 30 position on the pin, after the recoil and during the return of the barrel, a spring to return the breech-block and firing-pin to their operative positions to discharge the next cartridge, means in connection with the barrel and breech-block coupling, to release the 35 firing-pin from its extended position on the block after the latter has been locked to the barrel and means for arresting the firing-pin in the cocked position before the returning-spring 40 has been entirely released, substantially as described.

2. In an automatic firearm, having a sliding barrel, the combination of a longitudinally-guided non-revolvable firing-pin, an axially-revolvable cylindrical breech-block telescopic- 45 ally movable thereon, means for uncoupling and recoupling the said block and pin and block and barrel on the return of the barrel after the recoil and retaining the pin in the 50 firing position as specified, a pivotally-mounted spring-pressed detent-lever and means for operating the same by the trigger to retain the firing-pin in its extreme rearward position at the end of the recoil substantially as de- 55 scribed.

3. In an automatic firearm having a sliding barrel, the combination of a longitudinally-guided non-revolvable firing-pin, an axially-revolvable cylindrical breech-block telescopic- 60 ally movable thereon, means for uncoupling and recoupling the said block and pin and block and barrel on the return of the barrel after the recoil and retaining the pin in the firing position as specified, a spring-operated 65 trigger 18, an auxiliary spring mounted at the rear of the same to force its finger toward the trigger-guard a nose on said trigger and a

notch in the lower part of the barrel into which said nose engages to prevent the barrel from longitudinal movement when the 70 trigger has been pushed toward the guard substantially as described.

4. In an automatic firearm having a sliding barrel, the combination of a longitudinally-guided non-revolvable firing-pin, an axially-revolvable cylindrical breech-block telescopic- 75 ally movable thereon, means for uncoupling and recoupling the said block and pin and block and barrel on the return of the barrel after the recoil and retaining the pin in the 80 firing position as specified, a spring-operated trigger 18, an auxiliary spring mounted at the rear of the same to force its finger toward the trigger-guard, a nose on said trigger and a notch in the lower part of the barrel into 85 which said nose engages to prevent the barrel from longitudinal movement, and a rearwardly-extending hook 40 on said trigger to engage over the end of the sear when the trigger has been pushed toward the guard by the 90 auxiliary spring substantially as described.

5. In an automatic firearm having a sliding barrel, the combination of a longitudinally-guided non-revolvable firing-pin, an axially-revolvable cylindrical breech-block telescopic- 95 ally movable thereon, means for uncoupling and recoupling the said block and pin and block and barrel, on the return of the barrel after the recoil and retaining the pin in the firing position as specified, an ejector-arm 100 having hook 45 and mounted on the rear barrel end, and a groove 47 in the breech-block in which said hook engages at times for the purpose substantially as described.

6. In an automatic firearm having a sliding 105 barrel, the combination of a longitudinally-guided non-revolvable firing-pin an axially-revolvable cylindrical breech-block telescopic- 110 ally movable thereon, means for uncoupling and recoupling the said breech-block and pin and block and barrel on the return of the barrel after the recoil and retaining the pin in the 115 firing position as specified, a pivotally-mounted spring-pressed detent-lever 49 having two arms 50 and 51 extending laterally into the cartridge-chamber and interior of the housing to retain the breech-block in its rearward position after the last cartridge has been fired substantially as described.

7. In an automatic firearm, having a sliding 120 barrel the combination of a longitudinally-guided non-revolvable firing-pin, an axially-revolvable cylindrical breech-block telescopic- 125 ally movable thereon, means for uncoupling and recoupling the said block and pin and block and barrel on the return of the barrel after the recoil and retaining the pin in the firing position as specified a slide 53 within the housing 1, having exterior handle and means for guiding the same longitudinally 130 and causing it to engage the firing-pin and operate the same when moved by hand substantially as described.

8. In an automatic firearm, having a sliding

barrel the combination of a longitudinally-guided non-revoluble firing-pin, an axially-revoluble cylindrical breech-block telescopically movable thereon, means for uncoupling and recoupling the said block and pin and block and barrel on the return of the barrel after the recoil and retaining the pin in the firing position as specified a cartridge-retaining lever 58 mounted to swing in the breech 10 and having a spring to normally hold the inner end in the path of the breech-block and above the top cartridge said lever being adapted to swing back after depression by the passing barrel and throw the previous cartridge-15 case out substantially as described.

9. In an automatic firearm having a sliding barrel, the combination of a longitudinally-guided non-revoluble firing-pin, an axially-revoluble cylindrical breech-block telescopically 20 movable thereon, means for uncoupling and recoupling the said block and pin and block and barrel on the return of the barrel

after the recoil and retaining the pin in the firing position as specified, a magazine-cover hinged to the under part of the butt, a cartridge-lifting lever hinged to the interior of said cover and having extending arm, a downwardly-spring-pressed bolt to depress said arm and raise the free end of said lever, a frame pivotally mounted on said lever-pivot 25 and a cartridge-lifting plate hinged to the free end of said frame and extending over the free end of said lever, the magazine-cover being so hinged as to be capable of swinging downwardly and bringing the cartridge-feed 30 lever out of operative connection with the said spring-bolt substantially as described.

In witness whereof we have hereunto set our hands in presence of two witnesses.
